PAPER CONTAINER FOR PASTRIES

Frederick O. Wickersham, Chicago, Ill.

Application November 3, 1947, Serial No. 783,665

6-Claims. (Cl. 206—1)

1

The invention relates to paper containers or cartons for fancy pastry.

One object of the invention is to provide a container for fancy pastry of the type which resembles a mushroom in contour and which includes a stem and a head which is usually coated with a frosting or soft cream. In handling and dispensing pastry of this type it is desirable to provide a container which supports each article so that the coating will not be marred or the article will not be broken.

Another object of the invention is to provide a container or carton for attractively packaging pastry of the mushroom or similar type, which readily permits inspection without removal from the container or carton.

Other objects of the invention will appear from the detailed description.

In the drawings, Fig. 1 is a perspective of the body of the container, illustrating the panels in their open position for inspection or removal of the pastry. Fig. 2 is a perspective of the body with the panels folded into their closed position. Fig. 3 is a perspective of the cover. Fig. 4 is a vertical section of the body with the cover thereon.

The invention is exemplified in a rectangular box-like body which comprises fixed and foldable side panels all formed of suitable paper such as cardboard or similar lightweight sheet material, and which are adapted to be held closed by a telescopic cover. This body comprises a rectangular base 10, and an upstanding side-panel 11 which forms a fixed side of the body and has a side-panel section 12 joined and extending at right angles thereto. Panel 10 and section 12 have their lower edge fixedly secured on base 10 and together form a fixed side and an adjoining side-section of the body which are fixedly secured to the base. An opposite side-panel 15 is fixedly joined and extends at right angles to a side panel section 13, which is foldably joined, at 14, to one edge of the fixed side-panel section 12. Panel 15 is foldable with panel section 13. Section 13 is foldable so it will be coplanar with section 12 and form therewith an intermediate side of the body between panels 11 and 15. A flap 16 is foldably joined at 17 to one edge of panel 15. A flap 18 is foldably joined at 19 to one edge of panel 11. These flaps are adapted to extend between panels 11 and 15 to form the side of the body opposite the side formed by panel sections 12 and 13. The joints between panel-section 12 and 13 and between flaps 16 and 18 and panels 11 and 15 may be formed by creas-

2

ing or scoring the cardboard. When the side panel 13 with section 12 and flaps 16 and 18 are folded to their closed position as illustrated in Fig. 2, they form a complete rectangular closure at all sides of the body above base 10 and when folded into their open position, as illustrated in Fig. 1, they provide free access to the interior of the container body.

A split or divided horizontal shelf for supporting the pastry includes a fixed section 25 which is fixedly secured to panel 11 and side-section 12 and a section 26 which is fixedly secured to foldable side panel 15 and side-section 13, and is foldable therewith. Shelf section 25 is firmly supported on side-panel 11 by vertical brackets 30 which are formed of cardboard and secured to said panel and said shelf section, so that the latter will be fixedly and horizontally supported relatively to base 10. In like manner, shelf-section 26 is firmly supported by brackets 31 of cardboard which are secured to the inner face of the foldable side panel 15 and to said shelf section. Shelf sections 25 and 26, when the body is folded to its closed position, are coplanar and mated to underlie and support the entire enlarged upper end or head 24 of the pastry. These shelf sections are provided with semi-circular cut-aways 27, which provide a circular opening in the shelf for confining the upper portion of the stem 23 of the pastry when the panels of the container body are in their closed position. An annulus or ring 22 is fixedly joined to the top face of the central portion of base 10 for retaining the lower end of the stem 23 of the pastry against displacement. When the foldable side panels are in their open position, the shelf-sections will be separated to permit the pastry to be placed in position in ring 22 and with a portion of the head 24 resting on shelf section 25. When the side panels are folded to their closed position, the shelf and section 26 will also underlie and support the head 24 of the pastry. The base 10 is pressed to form a rectangular shoulder 33 and is extended to provide a projecting rim 34. The shoulder 33 serves as a stop for the lower margin of foldable panel 13 and flaps 16 and 18. A horizontal tongue or flap 38 is fixed to the lower margin of panel 15 and is adapted to pass through a slot 39 in base 10 to vertically interlock the panel 15 and the base, when said panel is in its closed position.

A telescopic cover for the container body includes a top wall 36 and four depending sides 37 fixedly joined to said top. The bottom of the cover is open. The fixed sides 37 of the cover

extend to the base 10 and fit snugly around all sides of the body when the foldable panel side sections and flaps are in their closed position and hold them. The open bottom of the cover permits it to be slipped around the body and to be removed therefrom. The rim 34 on the base 10 projects laterally from the cover as an indication for preventing the container from being inadvertently inverted, and forms a stop at the lower end of the cover-sides 37.

In loading the container, the cover is removed and the foldable panel 15 and flaps 16 and 18 are swung into their open position as illustrated in Fig. 2. The pastry can then be readily deposited with its head 24 resting on shelf section 25 and the stem 23 extending into the annulus 22, so that the pastry will be supported in the body. The side-panel 15 and flaps 16 and 18 will then be folded to surround the pastry with the side-section 13 coplanar with the fixed section 12, the panel 15 opposite to the side-panel 11 and the flaps 16 and 18 coplanar, as illustrated in Fig. 2. The pastry will then be supported in the body against displacement and without its coated head contacting the sides of the body. The cover 37 will then be telescoped around the sides of the body of the container with its sides conforming to the sides of the body so that all sides will be secured in their closed position. When it is desired to inspect the pastry before purchase, the cover will be removed and the foldable members 16 and 18 may be swung apart, or the foldable front section 15 may be swung to its open position as illustrated in Fig. 2.

The invention exemplifies a cardboard container for fancy pastry of the mushroom type which can be readily loaded so that the coating thereon will be protected against marring, and which is foldable to surround the pastry and encloses it in secured position.

The invention is not to be understood as restricted to the details illustrated and described since these may be modified within the scope of the patent and claims without departing from the spirit and scope of the invention.

I claim:

1. A paper-container for packaging pastry comprising: a substantially rectangular base; a body including an upstanding section fixed to the base and an upstanding section foldably joined to the fixed section to swing laterally, said fixed and foldable sections forming three sides of the body, each section including a panel and a panel section extending upwardly from the side margins of the base; means foldable laterally relatively to the body-sections forming the fourth side of the body; a divided shelf spaced vertically from the base, including sections fixed on the fixed and movable body sections, respectively, for supporting an enlarged upper end of an article of pastry having a depending stem said shelf sections being cut away at their meeting line to provide an opening for the stem; a holder for said stem, fixed substantially on the center of the base, and a telescopic cover adapted to hold the foldable body section and said means closed.

2. A paper-container for packaging pastry comprising: a substantially rectangular base provided with a marginal shoulder; a body including an upstanding section fixed to the base and an upstanding section foldably joined to the fixed section to swing laterally, said fixed and foldable sections each including a panel and

a panel section, together forming three sides of the body and extending upwardly from the side margins of the base, said foldable section having its lower margin extended to abut against the shoulder on the base; means on the panels foldable laterally relatively to the body sections forming the fourth side of the body; a divided shelf spaced vertically from the base, including sections fixed on the fixed and movable body-sections, respectively, for supporting an enlarged upper end of an article of pastry having a depending stem said shelf sections being cut away at their meeting line to provide an opening for the stem; a holder for said stem fixed substantially on the center of the base, and a telescopic cover adapted to hold the foldable body section and said means closed.

3. A paper-container for packaging pastry comprising: a substantially rectangular base provided with a slot along one of its sides; a body including an upstanding section having its lower margin fixed to the base and an upstanding section foldably joined to the fixed section to swing laterally, said fixed and foldable sections forming three sides of the body and extending upwardly from the side margins of the base; means foldable laterally relatively to the body sections forming the fourth side of the body; a divided shelf spaced vertically from the base, including sections fixed on the fixed and movable body sections, respectively, for supporting an enlarged upper end of an article of pastry having a depending stem said shelf sections being cut away at their meeting line to provide an opening for the stem; a holder for said stem, fixed substantially on the center of the base; a lateral extension on the foldable section insertable into the slot in the base, for vertically interlocking the foldable section and the base, and a telescopic cover adapted to hold the foldable body section and said means closed.

4. A paper-container for packaging pastry comprising: a substantially rectangular base; an upstanding body-section including a panel and an angularly joined section having their lower margin fixed to the base and forming a fixed side and a section of an adjoining side; an upstanding foldable body-section including a side-section foldably joined to the fixed side-section to swing laterally and forming the remainder of said adjoining side and a panel to form the side opposite the fixed panel, said foldable panel and side-section extending upwardly from corresponding side margins of the base; means foldable laterally relatively to the body sections to form the fourth side of the body; a divided shelf spaced vertically from the base, including sections fixed on the fixed and foldable body sections, respectively, for supporting an enlarged upper portion of an article of pastry having a depending stem said shelf sections being cut away at their meeting line to provide an opening for the stem; a holder for said stem fixed substantially on the center of the base, and a telescopic cover adapted to hold the foldable body section and said means closed.

5. A paper-container for packaging pastry comprising: a substantially rectangular base; an upstanding body section including a panel and an angularly joined section having their lower margin fixed to the base and forming a fixed side and a section of an adjoining side; an upstanding foldable body section including a side section foldably joined to the fixed side section to swing laterally and forming the re-

mainder of said adjoining side and a panel to form the side opposite the fixed panel, said foldable panel and side section extending upwardly from the corresponding side margins of the base; means foldable laterally relatively to the body sections to form the fourth side of the body; a divided shelf spaced vertically from the base, including sections fixed on the fixed and foldable body sections, respectively, for supporting an enlarged upper portion of an article of pastry having a depending stem said shelf sections being cut away at their meeting line to provide an opening for the stem; an annular holder for said stem substantially on the center of the base; and a telescopic cover adapted to hold the foldable body section and said means closed.

6. A paper-container for packaging pastry comprising: a substantially rectangular base having a slot along one of its sides; an upstanding body section including a panel and an angularly joined section having their lower margin fixed to the base and forming a fixed side and a section of an adjoining side; an upstanding foldable body section including a side section foldably joined to the fixed side section to swing laterally and forming the remainder of said adjoining side and a panel to form the side opposite the fixed panel, said foldable panel and side section extending upwardly from corresponding side margins of the base; means foldable laterally relatively to the body sections

to form the fourth side of the body; a divided shelf spaced vertically from the base, including sections fixed on the fixed and foldable body sections, respectively, for supporting an enlarged upper portion of an article of pastry having a depending stem said shelf sections being cut away at their meeting line to provide an opening for the stem; a lateral extension on the panel of the foldable section insertable into the slot in the base for vertically interlocking the foldable section and the base; a holder for said stem substantially on the center of the base; and a telescopic cover adapted to hold the foldable body section and said means closed.
